UNITED STATES PATENT OFFICE.

WILLIAM F. FILE, OF TOPEKA, KANSAS, ASSIGNOR OF ONE-HALF TO C. S. SHEFFIELD.

NEWSPAPER-FILE.

SPECIFICATION forming part of Letters Patent No. 349,637, dated September 21, 1886.

Application filed December 5, 1885. Serial No. 184,842. (No model.)

To all whom it may concern:

Be it known that I, WILLIAM F. FILE, a citizen of the United States, residing at Topeka, in the county of Shawnee and State of Kansas, have invented certain new and useful Improvements in Newspaper-Files; and I do declare the following to be a full, clear, and exact description of the invention, such as will enable others skilled in the art to which it appertains to make and use the same, reference being had to the accompanying drawings, and to letters or figures of reference marked thereon, which form a part of this specification.

15 Figure 1 of the drawings is a side view of my file. Fig. 2 is a rear view of the same. Fig. 3 is a top view showing paper-file.

This invention has relation to newspaper-files; and it consists in the construction and 20 novel arrangement of devices, all as herein-after set forth, and pointed out in the claims.

In the accompanying drawings, the letter A designates the elongated body of the file, having the ledge or bearing B on its side extending lengthwise. From this ledge project the pins C C, said pins projecting upward or at 25 right angles to the ledge.

D D are bearings on the upper edge of the file-body A, to receive the journals E, which 30 carry the pressure-arms F, the ends of which are expanded or turned outward, so that they will have broad bearing on the paper which is placed on the ledge, the pins C passing through it. The pressure ends G of the pressure-arms 35 are designed to bear on the paper near the pins, holding the paper securely and preventing it from tearing away. The journals E are also each provided with a crank-arm, K, which is slotted to receive a stud, L, of the slide-bar 40 N, which works in engagement with a bearing, P, of the file-body, said bearing being preferably a groove, in order to lessen the size of the file, and to prevent the slide from being injured, the groove acting as a guard.

S represents a screw-threaded extension at 45 the end of the file, said extension being journaled in the file, as at T, so that it can be freely rotated. A threaded collar, V, on said extension is connected to an arm, Z, of the slide which operates the pressure-cranks. By turning the screw in one direction the slide is operated to raise the pressure-arms away from the ledge and pins, so that the paper can be readily disengaged from or introduced into the file. When the paper is placed in the file on 50 the ledge, as above indicated, it is readily secured by turning the screw in the opposite direction, this operation moving the slide-bar back and causing the pressure-arms to be forced into close contact with the paper. 55

Having described this invention, what I claim, and desire to secure by Letters Patent, is—

1. The combination, with a file-body, of 65 crank-pressure arms operating against a bearing-ledge of said body, a screw-extension and collar, and a bar connecting said collar and the pressure-cranks, substantially as specified.

2. A file-body having a ledge-bearing extending lengthwise on its side, and provided 70 with pins and movable pressure-arms operated by a threaded collar and extension-screw at the end of the file-body, substantially as specified.

3. The combination, with the grooved file- 75 body having a bearing-ledge, of the pivoted pressure-cranks connected to a slide-bar engaging said groove, and means for moving said slide-bar, substantially as specified.

In testimony whereof I affix my signature in 80 presence of two witnesses.

WILLIAM F. FILE.
